UNITED STATES PATENT OFFICE.

KARL GOETZ, OF DETROIT, MICHIGAN.

WINDOW-SASH.

1,335,492.

Specification of Letters Patent. Patented Mar. 30, 1920.

Application filed September 4, 1917. Serial No. 189,454.

To all whom it may concern:

Be it known that I, KARL GOETZ, a subject of the Emperor of Austria, residing at Detroit, in the county of Wayne and State of Michigan, have invented certain new and useful Improvements in Window-Sashes, of which the following is a specification, reference being had therein to the accompanying drawings.

10 This invention relates to metallic window sashes, and the object of my invention is to provide simple, durable and inexpensive and fire proof sashes embodying novel top, bottom, sides and meeting rails, having cross 15 sectional shapes insuring rigidity and holding means for plates of glass.

I attain the above and other objects by a mechanical construction that will be herein-after specifically described and then claimed, 20 and reference will now be had to the drawing, wherein—

Figure 1 is an elevation of the inner side of window sashes in accordance with my invention;

25 Fig. 2 is an enlarged cross sectional view taken on the line II—II of Fig. 1;

Fig. 3 is a similar view taken on the line III—III of Fig. 1;

30 Fig. 4 is a similar view taken on the line IV—IV of Fig. 1;

Fig. 5 is an enlarged fragmentary vertical sectional view taken on the lines V—V of Fig. 1;

Fig. 6 is an enlarged horizontal sectional 35 view taken on the line VI—VI of Fig. 1, and

Fig. 7 is a perspective view of a portion of one of the side rails of a sash.

Considering the top sash, there are metallic side rails B, a top rail A, and a meeting rail C. The top rail A is made of a single piece of sheet metal fashioned about a filler strip 1 of less length than the top rail, which has parallel side walls 2 and 3 with the 45 lower edges thereof forming a groove 4 to receive the upper edge of a glass plate 5 held by putty or other matter in the groove 4. Preferably one wall of the groove 4, at the inner side of the sash is of less length 50 than the outer grooved wall, as best shown in Fig. 2, so that the outer side of the glass plate 5 will have a substantial backing or brace. The upper edge of the wall 2 is bent inwardly at an inclination and upon itself to 55 provide a pocket 7 for the upper edge of the

wall 3, said wall being bent over the filler 1 and into the pocket 7, where it may be frictionally or otherwise held. The pocket 7 constitutes an overhanging ledge and permits of this portion of the window sash 60 being easily fitted in a window frame.

The ends of the top rail A are mitered and are adapted to be brazed, soldered, spot welded or otherwise connected to the upper mitered ends of the side rails B. The side 65 rails B are identical in construction and are formed somewhat similar to the top rail A, that is, each side rail is made of a single piece of metal bent about all sides of a filler 9 with inwardly projecting short and long 70 flanges 10 and 11 respectively forming a groove to receive the side edges of the glass plate 5 and putty or other securing means. The side flanges are formed by bending the metal on itself and after bending the metal 75 about the filler, the edges of the metal can be connected, as at 9^a, to form a longitudinal rib throughout the length of the rail, in a plane at a right angle to the plane of the flanges 10 and 11, so as to coöperate there- 80 with in adding rigidity to the rail. Instead of bending the flanges 10 and 11 inwardly at an angle, the flanges are in a plane with the side edges of the rail 3, as best shown in Fig. 6. The lower ends of the 85 side rails B are connected to the ends of the meeting rail C and the ends of the rails B and mitered, similar to the construction entering into the rail A. The meeting rail C is formed of a single piece of metal bent to 90 provide side walls 12 and 13 having the edges thereof connected by flanges 14. Soldered or otherwise secured to the wall 13 of the meeting rail is a channel strip 15 that receives the lower edge of the glass plate 5, 95 said channel strip being devoid of putty, as the putty in the grooves of the top and side rails is sufficient to hold the glass plate in position, and said channel strip is not placed in engagement with the meeting rail until 100 the glass plate has been properly assembled relative to the upper sash.

Reference will now be had to the lower sash composed of a meeting rail D, side rails E, and a bottom rail F. The side rails 105 E are constructed similar to the side rails B of the upper sash. The bottom rail F has two parallel walls 16 and 17 with the lower edges thereof terminating in a bottom lateral flange 18. The wall 17 has a channel 110

member 19, similar to the channel member 15, for supporting a plate of glass 20, said plate having the side edges thereof held in the side rails E by putty or other securing means 21. The upper edge of the plate of glass 20 extends into a groove of the meeting rail D, said groove being formed by bent portions of walls 22 and 23 of said rail, and said walls and the edges thereof connected by a lateral flange 24.

By reference to Figs. 3 and 6, it will be noted that the flange 14 of the upper sash is above the meeting rail D of the lower sash, and in consequence of such arrangement, the upper sash cannot be lowered or the lower sash raised, but provision is made for swinging the lower portion of the upper sash outwardly, by such devices generally designated 25 and forming no part of the present invention.

One embodiment of my invention has been illustrated, but it is to be understood that the structural elements are susceptible to such variations and modifications as fall within the scope of the appended claim.

What I claim is:

A metallic window sash composed of side rails, top and bottom rails, fillers in said side and top rails, and all of said rails having mitered ends secured together, each side rail being formed of a single piece of metal bent to provide two-ply flanges forming grooves adapted to receive the side edges of a pane of glass and a space for the filler of said side rail with the flanges and edges of the rail wholly outside of the filler space, each piece of metal having its longitudinal edges connected to form a rib in a plane at an angle to said flanges, and a channel member carried by the bottom rail of said sash and adapted to receive the lower edge of the pane of glass mounted in the grooves of said side rails.

In testimony whereof I affix my signature in the presence of two witnesses.

KARL GOETZ.
